CLAIM

I claim the ornamental design for a firearm magazine organizer, as shown and described.

DESCRIPTION

FIG. 1 is a right side view of the firearm magazine organizer. FIG. 2 is a left side view of the claimed design. FIG. 3 is a front view of the claimed design. FIG. 4 is a rear view of the claimed design. FIG. 5 is a top view of the claimed design. FIG. 6 is a bottom view of the claimed design. FIG. 7 is a perspective view of the claimed design; and, FIG. 8 is a cross-sectional view of the claimed design along line 8-8 in FIG. 5.

The broken lines appearing in FIG. 7 of firearm magazines are environmental matter forming no part of the claimed design.
